UNITED STATES PATENT OFFICE

2,602,575

NECK YOKE

Alvin Edmund Olson, Kelowna, British Columbia,
Canada

Application July 3, 1950, Serial No. 171,948

1 Claim. (Cl. 224—5)

1

My invention relates to improvements in neck yokes for supporting air or gas hose such as is used on percussion tools, spray guns, welding torches and the like, and also for flexible electric cables such as those used in electric welding or when using electrically operated power tools such as belt sanders, "skill" saws, polishing tools and the like.

The principal object of the invention is to provide means whereby the hose or cord carried by the worker will remain in fixed position about the worker's shoulders and neck and leave his arms perfectly free to carry on his work. A further object is to provide that any desired length of cord or hose may swing freely between the body of the user and the work to be done, so that there shall be no restriction of use of the tool.

Referring to the drawings:

Figure 1 is a perspective view of the yoke.

Figure 2 is a cross sectional view showing the neck band.

Figure 3 is a cross sectional view showing one of the clips secured adjacent the free ends of the yoke.

Figure 4 is a perspective view of a person using the device.

In the drawings like characters of reference indicate corresponding parts in each figure.

The numeral 1 indicates a length of rod or tube which is bent to form an inverted U-shaped member 2 having a base 3 and legs 4. The legs are bent adjacent the base so that the member may rest comfortably around the shoulders and neck of the user. The material used is preferably such that its curvature may be altered to suit the individual owner or user. A channel strip 6 which will preferably be somewhat in excess of 180 degrees in cross sectional circumference, is secured to and extends around the base 3 of the U-shaped member and is so disposed as to have its open side 7 facing rearwardly, as shown in Figure 1. This channel strip is desirably of a convenient size to

2 receive the hose of an acetylene torch or other tool.

5 Mounted on each leg 4 is one or more clips 9 which may be disposed adjacent the mid-length of each leg or adjacent to its free end. Each clip is desirably made of spring material and of a size to conveniently receive and lightly grip the hose or cord to be carried thereby.

10 The device as shown in Figure 4 is supporting a compressed air hose 11 leading to a paint spray 12, which hose is allowed to produce a bight 14 dropping slightly below the user's elbow. It will be noticed that the weight of the hose carried by the user's right hand is only half that of the bight 14 of said hose and that this weight is not increased irrespective of the position in which he has to support the paint spray.

15 It will further be realized that while the hose is not intended to be tightly gripped in the channel strip 6 or the clips 9, no displacement of the hose may take place inadvertently.

20 What I claim as my invention is:

25 A neck yoke comprising an inverted U-shaped member having a base and a pair of legs, said member being curved to fit the shoulders and chest of the user, a channel extending lengthwise of the base, the open side of said channel extending rearwardly and a clip secured to one of the legs, said channel and said clip being 30 adapted to releasably secure a flexible tool accessory to the U-shaped member.

ALVIN EDMUND OLSON.
